UNITED STATES PATENT OFFICE.

BERNARD KERN, JR., OF TOLEDO, OHIO, ASSIGNOR TO JOSEPH N. CLOUSE,
OF ST. LOUIS, MISSOURI.

PUZZLE.

SPECIFICATION forming part of Letters Patent No. 511,895, dated January 2, 1894.

Application filed January 13, 1893. Serial No. 458,258. (No model.)

To all whom it may concern:

Be it known that I, BERNARD KERN, Jr., a citizen of the United States, residing at Toledo, in the county of Lucas and State of 5 Ohio, have invented new and useful Improvements in Puzzles, of which the following is a specification.

My invention relates to improvements in amusement games in which two or more balls 10 or marbles are used one to designate a fox and the others dogs and the chase is around circular passages or tracks and up and down through dives to the burrow in the center of the game board.

15 The object of the game is to get the fox into the burrow ahead of the dogs; second, to keep the fox always in the lead of the dogs; also increasing the number of dogs makes the game more difficult to play; and a further 20 object is to have the tracks and passages so narrow that two of the marbles cannot pass in them. I attain these objects by the mechanism illustrated in the accompanying drawings, in which—

25 Figure 1, is a front or face view of the game block or board complete. Fig. 2, is a back view of the game block or board complete. Fig. 3, is a cross section of the game board or block taken on the dotted line X, X. Fig. 30 4 is a cross section of the game board or block taken on the dotted line Y, Y.

Like letters refer to like parts throughout the several views.

This is a game but the matter of this application pertains more particularly to the 35 shape and construction of the board upon which the game is played, it being designed in its upper and lower decks and their valleys and passages between them so as to 40 make such a game possible and difficult on it.

In the drawings the lower deck of the board 45 is represented by A, A, which may be made of wood or formed out of sheet metal. This lower deck A, A, is made with a depressed center portion as shown above the bottom C and a depressed exterior channel a, a, which is bounded by a peripheral flange. It is also provided with four radial channels D, D, D, D, which connect the central depression with 50 the exterior depressed circular channel a, a, and it further has four upward extending

radial channels E, E, E, E, which extend up and open onto the upper deck B, B. This upper deck B, B, is permanently attached to the top of the lower deck A, A. It is smaller 55 than the lower deck so as not to cover its exterior depressed channel a, a. This upper deck B, B, is made with a depressed center portion F, F, and a depressed exterior channel b, b, which is bounded by a peripheral 60 flange to prevent the marbles from rolling off as in the lower deck. This upper deck B, B, also has four radial inclined channels I, I, I, I, which connect the central depressed portion with the exterior depressed channel 65 b, b, which downward incline of the channel is from the center toward the outside. In the depressed center portion is permanently fixed a semi circular housing H, which is designed to be the home of the fox. The fox is 70 represented by marble No. 1, which is colored red and the dogs are represented by the marbles Nos. 2, 3, &c., which are colored dark or gray. This game board complete then is provided with an internal chamber between the 75 two decks from which are four passages leading to an exterior continuous channel. From this interior chamber there are also four upward extending passages which open onto the upper deck into an exterior continuous 80 channel from which there are four ascending passages to a central court around a housing. In all of these spaces and passages there is no place for two of the marbles to pass except in the court above and the chamber 85 below.

I design to make these game-boards of wood, sheet metal or paper.

Having thus described my invention, what I claim as new, and desire to secure by Letters 90 Patent, is—

1. In a game board, a smaller upper deck portion provided with a depressed central portion carrying a housing and connected with radial channels which extend to a depressed exterior channel from which radial 95 passages project downward into the lower deck's depressed central portion, as described and set forth.

2. In a game board the combination of an 100 upper and lower deck having connecting radial passages, an internal chamber formed

by a central depression in the lower deck, an upper court formed by a central depression in the upper deck in which there is a fixed housing and a depressed exterior valley 5 around each deck which connects by radial passages respectively to the internal chamber below and the court above, substantially as described and specified.

In testimony whereof I have hereunto set my hand in the presence of two subscribing to witnesses.

BERNARD KERN, JR.
